Franklin G. Neal.
ATTORNEY

UNITED STATES PATENT OFFICE.

CARL G. SWEBILIUS, OF NEW HAVEN, CONNECTICUT, ASSIGNOR, BY MESNE ASSIGNMENTS, TO THE MARLIN FIREARMS CORPORATION, OF NEW HAVEN, CONNECTICUT, A CORPORATION OF DELAWARE.

FIREARM.

1,422,238.

Specification of Letters Patent. Patented July 11, 1922.

Application filed September 24, 1919. Serial No. 325,636.

To all whom it may concern:

Be it known that I, CARL GUSTAF SWEBILIUS, a citizen of the United States, residing at New Haven, in the county of New Haven and State of Connecticut, have invented a new and useful Improvement in Firearms, of which the following is a specification,

This invention relates to improvements in firearms and is of especial utility in the automatic type.

In my copending application Ser. No. 239,360, filed June 11, 1918, I have disclosed an automatic firearm adapted for synchronous firing with the propeller of an airplane. The trigger mechanism of this gun is located in a housing carried by the receiver. This application is directed to the means of connecting the housing to the receiver.

It has been found highly desirable in all types of automatic guns to have the various elements thereof readily accessible and yet at the same time securely arranged in their proper places.

It is the object of this invention to provide a means for securing the above-mentioned housing or a similar attachment to the receiver in such a way that the housing may be readily removed but at the same time be firmly attached to the receiver.

An additional object of the invention is an attaching means which necessitates the tightening of but one connecting member to secure the housing to the receiver.

Referring now to the drawings,

Fig. 1 is a side elevation of the receiver with the housing attached.

Fig. 2 is a section on line 2—2 of Fig. 1, the trigger mechanism and breech bolt being omitted for the sake of clearness.

The reference numeral 1 designates the receiver of a gun to which is attached the housing 2, by means of an arrangement of elements to be described.

In the side wall of the receiver are cut two slots 3 and 4. These slots may be of any desired length or width. The outer end of each slot is undercut, and this cut is preferably, although not necessarily, a smooth surface oblique to the wall of the receiver. One end of the housing is shaped to provide a lug 5 somewhat shorter than the slot 3 but so shaped as to coact with the undercut in the outer end of said slot. At the other

end of the housing is an opening 6 through which extends the bolt 7. The head 8 of this bolt is shaped to coact with the undercut at the outer edge of the slot 4. A nut 9 is provided on the bolt, together with a lock washer 10.

To attach the housing 2 to the receiver 1, the housing is so tilted that the lug 5 may be inserted into the slot 3. With the nut 9 just engaged with the threads of the bolt 7, the latter is tilted slightly, the opening 6 being of sufficient size to allow it. The head of the bolt will thus clear the end of the slot 4 and may be inserted therein. The nut 9 is now tightened. The surfaces of the slots and of the head 8 and lug 5 are thus brought into contact. When the nut is tight, the housing is securely held in place on the receiver.

While my invention is disclosed in its use as means to attach a housing to an automatic gun, it is by no means limited to such use but is adapted for use wherever it is desired to attach one member to another.

It is, of course, understood that the particular device shown and described in the present application illustrates merely a preferred form of construction and arrangement of parts, which, it has been found, will successfully carry out the principles of my invention, and that various changes and modifications of details may easily be made without departing from the spirit of my invention as defined in the appended claims.

What I claim is:

1. A means of attaching one member to another, comprising two slots in one of the members, one end of each slot being undercut, a lug carried by the second member and adapted to coact with the undercut end of one slot and a draw bolt carried by said second member, said bolt having a head adapted to coact with the undercut end of said second slot.

2. A means of attaching a housing to the receiver of a gun, comprising two slots in the wall of the receiver, the outer ends of said slots being undercut, and heads carried by said housing adapted to coact with said undercuts, one of said heads being movable relative to said housing.

3. In a gun, a receiver, slots in said receiver, oblique surfaces at the outer ends of said slots, a rigid housing, oppositely-ar-

ranged oblique surfaces carried by said housing, and means for moving one of said oblique surfaces relative to said housing whereby the oblique surfaces of the housing are brought into holding engagement with the oblique surfaces of said receiver.

4. In an automatic gun; a receiver, a rig

housing carried thereby, and means for attaching said housing to said receiver, said means comprising coacting oblique surfaces 10 on said housing and receiver and means movable relative to said housing for forcing said surfaces into engagement.

CARL G. SWEBILIUS.
